UNITED STATES PATENT OFFICE.

ARCHIBALD J. ROBERTSON, OF CHICAGO, ILLINOIS.

CAR-WHEEL.

No. 895,685.

Specification of Letters Patent.

Patented Aug. 11, 1908.

Application filed October 31, 1907. Serial No. 399,981.

To all whom it may concern:

Be it known that I, ARCHIBALD J. ROBERTSON, a subject of the King of Great Britain, residing at Chicago, in the county of 5 Cook and State of Illinois, have invented certain new and useful Improvements in Car-Wheels, of which the following is a specification.

This invention relates to certain improvements in that class of wheels which are particularly designed and adapted for use on cars of various kinds, but with slight changes, is applicable for use on other vehicles; and has for its principal object to provide a 15 strong, reliable and efficient wheel, the parts of which shall be of such construction as to attain the greatest simplicity and facility in its manufacture, yet so as to afford great strength at the places required, and which 20 wheel shall comprise means for keeping the weight of the car or vehicle while subjected to a pulling or pushing force, slightly forward of the wheel-base with respect to the direction of motion, thus utilizing the said weight 25 to increase the effectiveness of the propelling force of the car applied at the axle of the wheel.

Various other objects and important advantages of the invention will be disclosed in 30 the subjoined description and explanation.

The invention consists in certain novel features and principles of the construction, combination and arrangement of the several parts of the improved wheel, as will be hereinafter fully set forth.

The novel features of the invention will be carefully defined in the claims.

In the accompanying drawing, which serves to illustrate the invention:—Figure 1 40 is an outer face view of the wheel embodying the invention, showing the parts in their normal positions. Fig. 2 is a central vertical sectional view taken on line 2—2 of Fig. 1 looking in the direction indicated by the arrows; and Fig. 3 is an enlarged sectional view, showing a modification in the manner of securing the annular plate to the body portion of the wheel, and illustrating in cross-section the peculiar and novel form of the 45 peripheral groove in the body part of the wheel, as well as the form of the rotatable rim which operates in said groove.

Like numerals of reference, refer to corresponding parts throughout the different 50 views of the drawing.

The body or inner rotating element of the wheel is designated by the reference numeral 5, and is provided with a central opening 6 for the reception of the axle upon which it may be mounted in any well known way. 60 In order to strengthen said portion and at the same time lessen its weight and economize in the amount of material used, it is provided on its inner face with a series of radially extending ribs 7 and a number of openings 8 arranged in a circle around the hub 9 or central portion of said part, as is clearly shown in Fig. 1 of the drawing. The outer surface of the body or inner portion 5 of the wheel, by which is meant that surface which 70 is presented outwardly from between the rails of a railway track, is formed with an annular recess or cutaway part 10, which extends from the periphery of the portion 5 inwardly to a suitable distance, and terminates 75 with a shoulder 11 at its inner portion.

The portion 5 of the wheel is formed in its periphery with a groove 12 to receive a portion of the rim or outer rotatable element 13 of the wheel, and said groove and the 80 tongue 14 or that portion of the rim 13 which fits and operates in the groove, are formed of a peculiar construction in cross-section, as will be seen and readily understood by reference to the arrows 15, 16 and 17 in Fig. 85 3 of the drawing, which arrows indicate the arcs on which the rounded portions of the groove and tongue 14 of the rim are struck or formed, so as to afford a greater bearing surface and greater strength in the direction 90 of the lateral thrust of the rim 13 against the body portion, which thrust is mainly in the direction indicated by the arrow 16 and substantially in a direction in alignment with the radial ribs 7, as will be readily understood. 95 Closely fitted in the annular recess 10 of the inner or body portion 5 is an annular plate 18, which has its inner periphery resting against the shoulder 11 of said recess. This plate may be secured in position by means of rivets 100 19 extended through suitable openings in the plate 18 and the body portion 5 near the groove 12 therein, or it may be secured in position by means of screw-bolts 20 and nuts 21 on the inner ends of said bolts, which 105 are also passed through suitable openings in the plate 18 and body portion 5 located as above stated. In order to enable the plate 18 to be more readily removed and also to prevent any possibility of warping or other- 110

wise deflecting the inner surface of the plate 18 by clenching the ends of the rivets 19, I prefer to use the screw-bolts and nuts shown in Fig. 3, but, of course, do not desire to be limited to the use thereof.

By reference to Figs. 2 and 3, it will be seen that the sides of the tongue 14 of the rim 13 are vertically disposed with respect to the body portion 5, and that the inner periphery 10 of the tongue 14 is formed to correspond with the cross-sectionally curved groove 12, so that said grooved portion of the body 5 will contact with the cross-sectionally curved inner periphery of the tongue 14 of the rim. 15 It will be further observed and understood that the annular plate 18 forms a portion of one of the walls of the groove 12, while the peripheral portion 22 on the inner face of the body portion 5 forms the other wall 20 of said groove, which walls are separated from the walls of the tongue at very small or infinitesimal spaces. The rim or outer rotatable element 13 loosely surrounds the body or inner portion 5 of the wheel, and has 25 on its periphery a flange 23 which is also rounded in cross-section, as shown, and is for the purpose of co-acting with the track rail.

It will be understood that as the outer circumference of the inner portion 5 is less 30 than the inner circumference of the rim 13, a certain amount of play will be provided for the inner portion with respect to the outer portion, and that the former will, therefore, be permitted to travel upon the inner periphery of the latter, and that the only resting place for the body or inner portion 5 will be on the inner periphery of the tongue 14 of the rim or outer part, and when power is applied to propel the vehicle the inner part 40 5 will be moved in advance of the vertical center of the outer part, whereby the load will be thrown forward of the wheel base, thus utilizing the weight of the vehicle to assist its own propulsion. While power is 45 applied, the load or weight of the vehicle will always be carried at an off-center point from the ground or rail contact.

In Fig. 1 of the drawing, the vertical line 2—2 represents the center of the wheel-base 50 line when the vehicle is at rest, and the inclined dotted line in said figure represents the direction in which the weight of the vehicle will be moved with respect to the wheel-base when power is applied at the axle to move the latter to the right.

From the foregoing and by reference to the drawing, it will be readily understood and clearly seen that the inner and outer rotating elements 5 and 13, respectively, will have 60 separate axes of rotation and differential speeds, but will co-operate in supporting the weight of the load, the inner one of said elements supporting the axle and the weight upon the other element, and the latter providing the wheel-base with respect to the

track. It is also apparent that the curved portion of the peripheral groove in the inner element will contact with the correspondingly curved tread portion or tongue 14 of the outer element or rim 13, but that the peripheries of the walls of the groove, which are the plate 18 and part 22, will not peripherally contact with the rim or outer element, thus reducing the friction incident to the contact of the inner and outer parts. By 75 providing the inner element with the annular recess 10 to receive the annular plate 18, it is apparent that the strain will be borne by the inner element and also that when it is desired to remove the rim 13 for repairs, or so 80 that a new one can be placed in its stead, the same may be done without removing the inner element from the axle. Other advantages attained by the peculiar construction above set forth of the rim 13 are, that it can 85 be more easily rolled into such a shape or form and that it permits the placing of the contact point between the inner periphery of the rim and the outer periphery of the inner element 5 further from the tread of the outer 90 rim, which is the track rail. The construction and arrangement of the inner and outer elements and the annular plate 18 also prevents dirt and other material from entering the groove 12, as is obvious. As the wheel 95 comprises two independently rotating elements, one of which travels or bears upon the other, it is evident that a desirable and beneficial reduction and distribution of the friction between the rails and wheels, especially 100 when rounding a curve, will be effected.

Having thus fully described my invention, what I claim as new, and desire to secure by Letters-Patent, is

1. In a wheel, the combination with an inner rotating element having in one of its surfaces an annular recess extending from its periphery inwardly and also a peripheral groove, of an annular plate secured to said element in the said recess by means of bolts extended transversely through said element and plate inwardly from the groove in said element and forming one of the vertical walls of the groove of the inner element, and an independently-rotatable rim supporting said element against the periphery of its groove.

2. In a wheel, the combination with an inner rotating element having in one of its surfaces an annular recess extending from its periphery inwardly and also a cross-sectionally curved peripheral groove, of an annular plate secured to said element in the said recess therefor and forming one of the vertical walls of the groove of the inner element, and an independently-rotatable rim having a cross-sectionally rounded tongue supporting said element against the periphery of its groove, the curved portions of said groove and tongue being so formed as to present the 130

lateral thrust of the rim upwardly and inwardly of the wheel in substantial alinement with the radial ribs thereof.

3. In a wheel, the combination with an inner rotating element having in one of its surfaces an annular recess extending from its periphery inwardly and also a cross-sectionally curved peripheral groove, of an annular plate detachably secured to said element in the 10 said recess therefor, and an independently-rotatable rim having a cross-sectionally rounded tongue supporting said element

against the periphery of its groove and provided with a rounded flange and body portion, the curved portions of said groove and tongue being so formed as to present the main lateral thrust of the rim upwardly and inwardly of the wheel in substantial alinement with the radial ribs thereof. 15
